PORTABLE SPRAYER

Ernest W. Jackson, P.O. Drawer 35, Austin, Tex.

Filed Aug. 16, 1962, Ser. No. 71,312

Term of patent 14 years

(Cl. D31—3)

FIG. 1 is a perspective view of a portable sprayer embodying my design;

FIG. 2 is a side elevational view thereof;

FIG. 3 is an end elevational view; and

FIG. 4 is a top plan view with the nozzle unit omitted for convenience of illustration.

The opposite side of FIG. 2 is substantially the same as the side shown and the bottom of the tank is substantially flat and unornamented.

I claim:

The ornamental design for a portable sprayer, substantially as shown and described.
